UNITED STATES PATENT OFFICE.

WILLIAM HICKS, OF DANVILLE, KENTUCKY, ASSIGNOR OF ONE-HALF TO
EDWARD B. RUSSEL, OF SAME PLACE.

DESIGN FOR AN IRONING-TABLE.

SPECIFICATION forming part of Design No. 19,852, dated May 27, 1890.

Application filed February 26, 1890. Serial No. 341,888. Term of patent 7 years.

To all whom it may concern:

Be it known that I, WILLIAM HICKS, a citizen of the United States, and a resident of Danville, in the State of Kentucky, have invented and produced a new and original Design for an Ironing-Table, of which the following is a specification.

A drawing accompanies this specification as part thereof.

10 The single figure represents a perspective view of an ironing-table embodying my said design.

This design relates to the shape of the ironing-table, and particularly of that portion 15 thereof below the plane of the ironing-board and iron-stand. Its leading features are a horizontal portion immediately below the plane of the ironing-board, having an outline at its rear end resembling the outline of the 20 superposed iron-stand, and an angular horizontal base extending rearwardly beyond the rear upright of the frame, the whole presenting a pleasing combination of straight and curved outlines, in connection with a tapering ironing-board having round ends which 25 forms part of the table and projects at what is herein designated the front end of the structure.

In the drawing, A represents said portion 30 of the table below the plane of the ironing-board and iron-stand.

B represents the ironing-board; C, the iron-stand, and D the crank-shaped head of a hand-screw.

The uppermost horizontal part of said portion A has curvilinear lateral edges *a* and a straight rear edge *b*, making the outline of its rear end resemble that of the superposed iron-stand C, which may be otherwise of any approved design, but preferably of open-work. 35 The uprights *c c²* are rectangular and flat, with edges toward the sides of the table, and the front upright *c²* is crossed by straight pieces *d d²* on the respective sides of the table, extending obliquely upward from the rear 40 upright *c* and disappearing in the figure below the ironing-board B. The base *e* of said portion A is substantially of T shape in plan, with its longitudinal member double, so as to inclose the lower ends of the uprights *c c²*. 45 The protruding rear ends of said longitudinal member of the base, the upper corners of its transverse member, and the ends of a superposed cross-bar *f* at the rear end are preferably corner-beveled in harmony with the 50 general design, which calls for angles and straight lines below and straight lines and curves at top.

Having thus described my said design, I claim and desire to patent under this specification—

The design for an ironing-table, substantially as shown and described.

WILLIAM HICKS.
